(57) **CLAIM**

I claim, the ornamental design for a hub for pipeline inspection device, as shown and described.

DESCRIPTION

FIG. 1 is a first perspective view of a hub for a pipeline inspection device embodying the invention.

FIG. 2 is a second perspective view of the hub of FIG. 1.

FIG. 3 is a rear view of the hub of FIG. 1.

FIG. 4 is a front view of the hub of FIG. 1.

FIG. 5 is a top view of the hub of FIG. 1.

FIG. 6 is a bottom view of the hub of FIG. 1.

FIG. 7 is a first side view of the hub of FIG. 1; and,

FIG. 8 is a second side view of the hub of FIG. 1.

The broken line shown in the drawings are for the purpose of illustrating portions of the hub for pipeline inspection device and form no part of the claimed design.
